UNITED STATES PATENT OFFICE.

AXEL JULIUS TUNÉR, OF GOTTFENBORG, SWEDEN.

MUSIC-LEAF TURNER.

Application filed July 25, 1924. Serial No. 723,233.

To all whom it may concern:

Be it known that I, AXEL JULIUS TUNÉR, a subject of Kingdom of Sweden, residing at Gottenborg, Sweden, have invented certain new and useful Improved Music-Leaf Turners, of which the following is a specification.

This invention relates to apparatus for turning over the leaves in a music book mechanically, when playing, so that the performer need not interrupt his execution for the purpose of turning the leaves by hand.

The object of this invention is to provide an apparatus of the class mentioned, which is ready for use and easy to operate by means of the foot or by the knee.

Another object of the invention is to provide a leaf turning apparatus, which is quick, reliable and silent in its operation.

A further object of the invention is to provide an apparatus of the class mentioned, which is rather cheap in construction and which can be easily applied on any music stand, such as usually used by a violin player as well as music stands on pianos or the like.

Further advantages of the improved music leaf turner will be clearly understood from the following description and the drawings relating thereto.

An embodiment of the invention is illustrated in the accompanying drawings, wherein

Fig. 1 is a side view elevation of a music stand of the common type with the improved device applied.

Fig. 2 is in a larger scale a view of the rear side of the music stand showing the new apparatus attached.

Fig. 3 shows the same parts as in Fig. 2, but from the front side and with the apparatus during the first stage of operation.

Fig. 4 is the same view as Fig. 2, but with the apparatus in position to turn back a leaf, in order to play the same piece a second time.

Fig. 5 is a plan view of Figure 2 showing the apparatus in a somewhat later stage of operation than in Fig. 3.

Fig. 6 is a view of the same character as Fig. 5, but illustrating the position of the apparatus before the completion of the turning movement.

Fig. 7 is a side view of the apparatus proper, and

Fig. 8 is a sectional view on the line 8—8 of Fig. 2.

Fig. 9 is a fragmentary plan detail of a means for reversely turning the leaves.

In all the figures the same references refer to same parts.

The music stand is shown of the common type, comprising a stanchion 1 on three feet 2 and carrying a table 3 for the music book 4. On the rear side of the table 3 the mechanical leaf turner 5 is attached and can be operated by the foot of the performer by means of a pedal 6, connected by the horizontal pivot 7 to one of the stanchion feet 2 and connected to the apparatus 5 by means of a cord 80.

The upper edge of each leaf of the music book 4, which is to be turned over mechanically, is provided with a little hook 9 made of some thin and stiff material such as sheet metal, card board or the like, which hook comprises a tongue 9' projecting horizontally and parallel to the leaf edge and crossing a narrow slot 10 in the said edge. The hook 9 can be attached directly to the leaf proper by means of small barbs 11 drawn through the paper and clinched on the rear side thereof or in any other convenient way. It is also advantageous to apply the hooks 9 and the slots 10 upon narrow strips 12 of paper, which are attached to the leaves along the upper edge thereof by means of glue or the like, by which device the leaves are saved from being injured by the cuts 10 as well as the barbs 11. Such glued strips 12 armoured with the hooks 9 and cuts 10 can then be kept in store by stationers or such dealers and sold ready for use, so that the purchaser needs only to moisten the glued strips and apply them on the leaves of their music books. Fig. 9 illustrates such an armoured and glued strip.

The turning apparatus proper comprises a screw-threaded member 13, the threads of which have a rather large pitch such as known from drills or the like. On the upper portion 14 of the member 13 the pitch of the threads is infinite, so that the threads on this portion act merely as a guide for a nut 15, mounted upon the screw 13 and provided with a downwardly directed strap 16 of a double bent wire or the like. The screw member 13 is carried in a collar 17 by a base plate 18, which is attached to the rear side of the table 3. The lower end of the screw member 13 rests upon an apron 19 projecting from the base plate 18 and form-

- ing a thrust bearing for the member 13. The nut 15 is provided with a downwardly projecting portion 20 with a trunnion 21, upon which is pivoted a lever 22. A spiral 5 spring 113 encircles the screw member 13 and is disposed between the nut 15 and the projection 19 so as to keep the nut yielding-
ly in its upper position illustrated in Figs. 2 and 7.
- 10 The lower arm of the lever 22 is tapered so as to form an inclined plane 23, which cooperates with a stud or a roller 24, projecting from the base plate 18. The upper arm of the lever 22 is forked so as to form 15 two fingers 22' and 22'' for the purpose described below, and a clock spring 25 around the fulcrum of the lever 22 tends to keep the lever normally in such a position, that the tapered end portion 23 rests against the stud or roller 24 such as shown in Fig. 2.
- 15 Another lever 26 is pivotally mounted on the base plate 18 by means of a stud 27, and by the influence of a spring 28, which is supported by a stud 29 on the base plate 18, is kept normally in the position shown in Fig. 2. When the nut 15 is lowered to the position illustrated in Fig. 4, a projection 29' on the nut 15 cooperates with the lower arm 26' of the lever 26 so as to push the upper 20 arm of said lever against the action of the spring 28 to the right according to Fig. 4 for the purpose described below.
- 20 The upper end 13' of the screw member 13 carries a sleeve 30 with an axial slot 31, and within said sleeve there is slidably mounted a turning arm 32, which projects horizontally along the hook provided upper edges of the leaves of the music book 4 when in position on the table 3. The turning arm 25 32 on the end portion within the sleeve 30 is provided with a finger 33, which projects through the slot 31 and serves for several purposes. One of these purposes is to keep the turning arm 32 in proper position within the sleeve 30, so that the turning arm is 30 prevented from rotation around its axis, and another purpose is to limit the sliding amplitudes of the turning arm within said sleeve.
- 25 The free end 34 of the turning arm 32 is bent downwards at right angle to the turning arm proper, and the uttermost end 35 of said end portion is bent outwardly to form a hook which extends from the table 3, when the rod 32 is in its normal initial position 35 as illustrated in Figs. 2 and 7. At some distance from the double bent end portion 34, 35 the turning arm 32 is provided with another hook shaped member 36, 37 of mainly the same shape as the double bent portion 34, 35, but with the hooked end 37 directed oppositely to the hooked end 35.
- 30 The described apparatus operates as follows.

When playing from the notes appearing 65 on the leaf of the music book 4 just being

opened the pedal 6 is left untouched and thereby held in its upper position as shown in Fig. 1 by the influence of the spring 113 and the cord 80. In this position the turning arm 32 remains in the position illustrated in Fig. 2. When the performer desires to turn the above mentioned leaf the pedal 6 is depressed, and this motion causes the strap 16 to descend against the spring 113, bringing with it the nut 15 as well as 70 the lever 22. On account of the infinite pitch of the threads of the upper portion 14 of the screw member 13 the descending motion of the nut 15 has no influence upon the member 13, which consequently remains 75 stationary, but the said descending motion of the lever 22 causes the inclined plane 23 to slide along the stud or roller 24, and by means thereof said lever 22 swings on its pivot 21 to the position shown in Fig. 3. By 80 this motion the finger 22'' coacts with the finger 33 and by means thereof pushes the turning arm 32 to the right in Fig. 2 or the position illustrated in Fig. 3. As a result the hooked end 34 is positioned below the 85 hook tongue 9', so that, when the downward motion of the nut 15 is continued by a further depression of the pedal 6, the nut 15 is caused to cooperate with the operative portion of the threads of the member 13, whereby said screw member is caused to revolve, bringing with it the sleeve 30 and the turning arm 32, said arm catching the leaf of the music book 4 by the hook 9, 9' and brings 90 said leaf to be turned as illustrated in two stages by Figs. 5 and 6 respectively, the arrows in said figures showing the moving direction of the turning arm 32. In the position shown in Fig. 6 the leaf in question falls down into its reversed position by its 95 own gravity, whereby the hooked end 34 of the turning arm 32 passes by freely through the slot 10.

As soon as the leaf has been reversed, the 100 pedal 6 is released, and the spring 113 pushes the nut 15 upwards lifting the pedal 6 into its initial position and causing as well the turning arm 32 to be swung back into the position of Fig. 2, whereby the lever 22 is released from the stud or roller 24, so that 105 the clock spring 25 is able to swing back the lever 22, whereby its finger 22'' releases the finger 33, and the finger 22' comes into contact with the end 32' of the turning arm 32, pushing said rod back to the initial position shown in Fig. 2 ready for turning the 110 next leaf.

Sometimes it happens, that some notes already played must be repeated, and if such 115 notes appear on a leaf already turned over, said leaf must be reversed. Such an operation also can be performed by means of the present apparatus. For this purpose all the leaves of the music book 4 or at least those 120 of them, which must be able to be reversed, 125 130

are provided with a further hook 109, 109' of the very same appearance as the hook 9, 9' but applied in a reversed position as shown in Figs. 2-6 and 9. These hooks also 5 must be provided with a slot 110 of the same type as the slot 10 and they can be applied either directly on the leaves of the music book 4 or on the strip 12. The hooks 109, 109' are provided to cooperate with the 10 hook member 36, 37 on the turning arm 32, which occurs, when the nut 15 by aid of the pedal 6 is pushed downwards so far, that the projection 29' comes in cooperation with the lever arm 26', whereby the lever 26 is 15 caused to swing around its fulcrum 27 as shown in Fig. 4. Then the upper end of the lever arm 26 contacts with the end 32' of the rod 32 or with a finger 32'' thereupon, causing the rod 32 to be pushed to the right in 20 accordance with Fig. 4 to such an extent, that the hook 36, 37 is positioned below the hook tongue 109'. The pedal 6 is released, so that the turning arm 32 can be swung back into its initial position in Fig. 2, the turning arm 32 bringing the leaf of the music book 4 with it back, so that the notes on its proper side will appear once again for the performer.

The small hooks 35 and 37 respectively 30 have for their objects to prevent the hook tongue 9', 109' respectively to slip down from the grasp of the hook 34, 36 respectively.

It is evident, that the constructive performance of the various parts can be designed in a plurality of forms without exceeding the scope of this invention, and I do not want to limit myself exactly to the design shown in the drawings and here described in detail. Such variations, however, can easily be understood by every one skilled in the art, and therefore they need not be described or illustrated.

What I claim is:

- 45 1. In a music leaf turner, in combination, hooks on the leaves, a hook shaped turning arm provided to coact with said hooks, a screw threaded member carrying said turning arm, an axially movable nut cooperating with said screw threaded member so as to revolve said member, a double armed lever pivotable around a fulcrum and connected with said nut, the one end of said

lever formed as an inclined plane, a stationary member coacting with said inclined plane so as to swing the lever around its fulcrum, the other arm of said lever coacting with the turning arm so as to slide the same transversely of the axis of the screw threaded member, and means operable by 60 the leg of the performer for imparting axial movement to the nut to effect operation of the turning arm.

2. In a music leaf turner, in combination, hooks on the leaves, a hook shaped turning arm provided to coact with said hooks, means to bring the turning arm in coaction with said hooks, means to revolve the turning arm so as to turn over a leaf, means to slide said turning arm transversely to 70 the revolving axis of the same, other hooks on the leaves directed reversely with respect to the first mentioned hooks, another hook on the turning arm provided to cooperate with said reversely directed leaf hooks and 75 means to move the turning arm so as to bring its last mentioned hook to coact with said reversely arranged leaf hook for the purpose to reverse a previously turned leaf.

3. In a music leaf turner, hooks at the 80 upper edges of the leaves, said edges of the leaves having slots crossed by the hooks, a screw threaded member journalled parallel to the turning edge of the leaves, a nut slideable along the screw threaded member so 85 as to revolve same, a spring tending to keep said nut in its upper position, pedal operated means to cause said nut to descend against the spring action, a turning arm mounted on the upper end of said screw 90 threaded member, a hook at the end of said turning arm provided to coact with said hooks on the leaves, a lever provided to descend together with the nut, an inclined plane on the one end of said lever, a stationary member coacting with the inclined plane so as to push the turning arm into coaction with said leaf hooks when said nut descends, and to push said turning arm in the opposite direction when the nut ascends, 100 and means to automatically bring said turning arm back into its initial position.

In testimony whereof I have hereunto affixed my signature.

AXEL JULIUS TUNÉR.
